(57) **CLAIM**

The ornamental design for a foldable top for a portable poker table, as shown and described.

DESCRIPTION

FIG. 1 is a perspective view of a foldable top for a portable poker table, showing my new design; the broken lines are for environmental purposes only and form no part of the claimed design;

FIG. 2 is a top view thereof;

FIG. 3 is an enlarged sectional view thereof taken in the direction of the arrows upon line 3—3 of FIG. 2;

FIG. 4 is a bottom view thereof;

FIG. 5 is a bottom view in the folded state;

FIG. 6 is an equivalent alternative embodiment comprising the embodiment exemplified in FIGS. 1—5 further provided with a removable unfolded upper layer; and,

FIG. 7 is an enlarged sectional view taken in the direction of the arrows upon the line 7—7 of FIG. 6.
